UNITED STATES PATENT OFFICE.

JOSEPH SCHLOSS, OF NEW YORK, N. Y., ASSIGNOR TO H. WALLACH'S SONS, OF SAME PLACE.

DESIGN FOR A CAMPAIGN-SHIRT.

SPECIFICATION forming part of Design No. 21,664, dated June 28, 1892.

Application filed May 16, 1892. Serial No. 433,223. Term of patent 14 years.

To all whom it may concern:

Be it known that I, JOSEPH SCHLOSS, a citizen of the United States, residing at New York city, in the county and State of New York, 5 have produced a new and original Design for Shirts, of which the following is a specification.

In the drawings I have represented what is known to the trade as a "double-breasted shirt" embodying the features of my design.

The leading feature of my design consists of a shirt having a shield-shaped front which has upon its upper part a number of stars, while the lower part has upon it a number of 15 contrasting stripes or lines running at substantially right angles to the upper part, as shown in the drawing.

In the accompanying drawing, X is the shirt-body, X' the sleeves, and X" the collar. 20 A is the shield-shaped front, divided into an upper part B and a lower part C, and has upon one side buttonholes. The shirt is provided with the usual buttons. The upper part B contains the stars, while the lower part, which is gracefully rounded, has upon it the contrasting stripes, as shown in the drawings. The upper part B has formed upon its upper edge three points 1 2 3, equidistant from each other, and between these three points are formed two sloping curves 4 and 5, which connect said points. The central point 2 comes at the intersection of the collar ends, and the other points 1 and 3 extend just in front of the shoulders.

What I claim is—

The design for a shirt, substantially as herein shown and described.

In testimony whereof I have hereunto signed my name this 12th day of May, A. D. 1892.

JOSEPH SCHLOSS.
